SPOON OR SIMILAR ARTICLE

Isadore Albert Lipman, Meriden, Conn., assignor to Amston Silver Company, Inc., Meriden,
Conn., a corporation of Connecticut

Application February 14, 1951, Serial No. 14,211

Term of patent 14 years

(Cl. D54—12)

To all whom it may concern:

Be it known that I, Isadore Albert Lipman, a citizen of the United States and residing at Meriden, in the county of New Haven and State of Connecticut, have invented a new, original, and ornamental Design for a Spoon or Similar Article, of which the following is a specification, reference being had to the accompanying drawing, forming a part thereof.

Fig. 1 is a front view of a spoon showing my new design.

Fig. 2 is a back view of the spoon.

Figs. 3 and 4 are cross sections taken along the lines 3—3 and 4—4, respectively, of Fig. 1.

The essential features of the design of my invention reside in the configuration of the handle in combination with the particular type of ornamentation applied thereto.

I claim:

The ornamental design for a spoon or similar article, as shown and described.

ISADORE ALBERT LIPMAN.
